UNITED STATES PATENT OFFICE.

CHARLES B. GAMBLE AND FREDERICK C. SHEPARD, OF MINNEAPOLIS, MINNESOTA.

HEADLIGHT-DIMMER.

1,214,909.

Specification of Letters Patent. Patented Feb. 6, 1917.

Application filed April 8, 1916. Serial No. 89,785.

To all whom it may concern:

Be it known that we, CHARLES B. GAMBLE and FREDERICK C. SHEPARD, citizens of the United States, residents of Minneapolis, county of Hennepin, State of Minnesota, have invented certain new and useful Improvements in Headlight-Dimmers, of which the following is a specification.

The object of our invention is to provide a means for dimming the headlights of automobiles, trucks, street cars and the like, which can be made effective from the driver's seat while in the thickly traveled portions of the city, and be as easily rendered inactive and the full rays of the light be thrown on the roadway while traveling in the rural districts.

A further object is to provide an inexpensive device which can be attached to an ordinary headlight without material modification.

Other objects of the invention will appear from the following detailed description.

The invention consists generally in various constructions and combinations, all as hereinafter described and particularly pointed out in the claims.

In the accompanying drawings forming part of this specification,

Fig. 1 is a view of a headlight with our improved dimmer applied thereto,

Fig. 2 is a detail view, showing the electromagnets and cores therefor arranged when energized to attract the armature to shift the dimmer blades,

Fig. 3 is a detail view, showing the manner of mounting the shutters or blades on the dimmer in the rear of the light lens,

Figs. 4 and 5 are detail views, showing the manner of mounting the dimmer blades,

Fig. 6 illustrates a modified construction of a mechanical device for operating the blades.

In the drawing, 2 represents a headlight of the ordinary type now generally used in modern cars. This light is provided with a cone-shaped reflector 3 and with a door 4 for the lens 5. 6 is a ring in the form of a Z-bar in cross section, secured by clips 7 to the door and provided with a flange 8 in a plane parallel with the plane of the lens in which the dimmer blades are mounted. These blades, which I will designate by reference numeral 9, are preferably of sheet metal and substantially of the same form,

but vary in length and width to adapt them for the different positions in the door of the lamp. These blades have key-hole slots 10 and 11 formed therein and the flange 8 has similar slots to coöperate with the slots 10 when the dimmer blades are mounted in the ring and form a hinge support at each end of the blades. A semi-circular band 12 is provided, made preferably of angle iron and having slots therein to coöperate with the slots 11, said band being in a plane parallel with the plane of the ring 6 and held in place thereon by spring clips 13. A spring 14 is provided at the top of the band 12 for normally holding it in position to present the longitudinal edges of the dimmer blades to the rays of light and present practically no obstruction to the passage of the rays, vertical movement of the band 12 to tilt the dimmer blades being against the tension of the spring 14. An armature 15 is mounted in the lamp 2 and provided with a core 16 having a forwardly turned end that is adjacent to the steel band 12 so that when this core is energized by the closing of the circuit through the electro-magnet, the band 12 will be attracted to swing the blades from the position indicated in full lines in Fig. 2 to that shown in dotted lines, whereupon the rays of light will be obstructed and while the upper portion of the lens will appear light to an observer standing in front of the car, there will be no brilliant rays projected to dazzle the driver of an approaching car or a pedestrian.

The electro-magnet 15 is connected with a conductor 17 which leads to a battery B and switch S. Contact points 18 and 19 are provided and when the switch is in circuit with the contact 19 the current will be directed from the batteries through the magnets to energize the core thereof. The contact 18 is in a branch circuit 20 having a resistance coil 21 therefor, so that when the switch is shifted from the point 19 to the point 18 the power of the magnet will be reduced but will be sufficient to hold the armature band in the position indicated by dotted lines in Fig. 2, with the dimmer blades adjusted to cut off the rays of light through the lens. As soon as the switch is moved to break the circuit, the tension of the spring 14 will return the blades to their normal open or horizontal position.

The different positions of the blades are

indicated by the section lines in Fig. 4, the normal or open position being shown by full lines in section, while the dotted lines indicate the raised position of the armature and 5 the blades in their inclined or dimming position.

Fig. 5 illustrates a horizontal sectional view through the ring and the armature and the manner of mounting the blades 10 thereon.

In Fig. 6 a modified construction is shown, which consists in providing a slide 22 having guides 23 on the lamp, one end of the slide being connected to the armature 12 and a 15 bell crank 24 being pivoted at 25 and having a loose connection at 26 with the slide. The opposite end of the bell crank has an adjustable connection with a wire which extends to a point within convenient reach 20 of the driver of the car. A coil 28 incloses this wire and braces it sufficiently to allow the driver to apply pressure lengthwise of the wire to shift the bell crank 24 and the semi-circular armature band to close or open 25 the dimmer blades as may be desired.

This device is designed for use particularly on the city streets where the blinding glare of the headlights is objectionable, the circuit being closed through the magnets as 30 long as it may be desired to use the dimmer, connection being made with the dynamo and battery circuit of the car. When the car approaches a country road or the out-lying districts of the city, where the streets 35 are poorly lighted or not at all, the circuit may be broken, whereupon the spring will return the dimmer blades to their normal horizontal position and the undimmed rays from the headlight will then be thrown in 40 advance of the car in the ordinary way.

We claim as our invention:

1. The combination, with a headlight and its reflector, and a lens and a lens cap therefor, of a ring mounted in the rear of said lens and having oppositely arranged slots therein, dimmer blades having slotted ends to enter the slots in said ring and mounted to oscillate with respect thereto, said blades extending across the upper half substantially 6 of said lens, means for tilting said blades to divert the rays of light downwardly, and means for returning said blades to their normal position.

2. The combination, with a headlight and its reflector and a lens and a lens cap therefor, of a ring mounted in the rear of said lens, a semi-circular band arranged in the rear of the upper portion of said ring, dimmer blades having their ends loosely 10 mounted in said ring and also in said band, means supporting said band on said ring and permitting its vertical movement with respect thereto, and mechanism for raising

and lowering said band to close or open said blades.

3. The combination, with a headlight, of a plurality of dimmer blades having slotted ends, a curved member having slots to receive the ends of said blades for oscillation in the rear of the light lens, an armature connected with said blades for oscillating them simultaneously, electro-magnets having their pole pieces adjacent to said armature, and a switch for controlling the electric circuit through said magnets.

4. The combination, with a headlight, of a plurality of dimmer blades, a member having opposing slots to receive the ends of said blades, an armature having slots to receive said blades for oscillating them simultaneously, electro-magnets having their pole pieces adjacent to said armature, an electric circuit for said magnets, a switch, contact points therefor in said circuit, and a resistance coil in circuit with one of said contact points.

5. The combination, with a headlight, of a plurality of dimmer blades mounted for oscillation in the rear of the light lens, an armature, semi-circular in form, connected with said blades for oscillating them simultaneously, a spring for normally holding said blades in position to direct the rays of light forwardly through said lens, an electro-magnet having its pole pieces adjacent to 95 said armature and an electric circuit for said magnet, the energizing of said magnet attracting said armature to tilt said blades to an oblique position, and means for returning said blades to their normal position 100 when the circuit is broken through said magnet.

6. The combination, with a headlight and its reflector and a lens and lens cap therefor, of a series of dimmer blades mounted to 105 oscillate in the rear of said lens and extending across the same, said dimmer blades having slotted ends and a curved member having slots therein for receiving said dimmer blades for tilting them simultaneously, and means for operating said curved member.

7. The combination, with a headlight, of a plurality of dimmer blades arranged in parallel relation and having bearings at their ends in the rear of the light lens and 115 free to rock in said bearings, a curved member partially encircling said blades and having means for engagement with the ends thereof for rocking said blades in their bearings, and means for moving said curved 120 member vertically to operate said blades.

In witness whereof, we have hereunto set our hands this 17 day of March 1916.

CHARLES B. GAMBLE,
FREDERICK C. SHEPARD.
